Patented Sept. 2, 1975

236,595

LIQUID SAMPLER

Charles Laird McClure, Malvern, Pa., assignor to
Pro-Tech Inc., Malvern, Pa.

Filed Feb. 28, 1974, Ser. No. 447,052

Term of patent 14 years

Int. Cl. D10—05

U.S. Cl. D10—81

Fig. 1

Fig. 2

*Fig. 3**Fig. 4**Fig. 5*

FIG. 1 is a top front perspective view of a liquid sampler showing my new design with the cover closed;

FIG. 2 is a top front perspective view thereof with the cover open;

FIG. 3 is a top plan view of FIG. 1;

FIG. 4 is a right side elevational view of FIG. 1; the left side being a mirror image thereto;

FIG. 5 is a rear elevational view of FIG. 1.

The bottom, not shown, is plain except for the protruding feet shown in elevation.

I claim:

The ornamental design for a liquid sampler, as shown and described.
